UNITED STATES PATENT OFFICE.

BERT DECK, OF WINFIELD, KANSAS.

SEPARATOR FOR FEEDERS.

Application filed May 6, 1922. Serial No. 558,906.

To all whom it may concern:

Be it known that I, BERT DECK, a citizen of the United States, residing at Winfield, in the county of Cowley and State of Kansas, have invented new and useful Improvements in Separators for Feeders, of which the following is a specification.

This invention has reference to a sheet separating and moving device for printing presses.

The primary object of the invention is to produce in combination with the suction feet employed for elevating the upper sheet from the remainder of a pile of sheets to a position where the said sheet may be grasped by the grippers, blower feet which may be removably secured on the ordinary suction feet and which will at the proper time inject a blast of air between the upper and the next sheet thereto on the pile so that any tendency of the sticking of the upper sheets by static electricity or other causes will be overcome, and the accurate removal of the upper sheet positively assured.

The drawings which accompany and form part of this application, illustrate a satisfactory embodiment of my improvement reduced to practice, but I wish it understood that changes may be made in the mechanism described and shown without exceeding the scope of my invention as defined in the appended claims.

In the drawings:—

Figure 1 is a top plan view showing my improvement arranged upon the end suction feet on the separator bar of a printing press.

Figure 2 is a view looking toward the rear of the separator bar, parts being in section.

Figure 3 is a sectional view approximately on the line 3—3 of Figure 2.

Figure 4 is a sectional view on the line 4—4 of Figure 3.

Figure 5 is a perspective view of the improvement.

Figures 6, 7 and 8 are longitudinal sectional views through the improvement showing the same arranged on varying classes of suction feet.

As the manner in which suction feet on printing presses act to raise the top sheet from the remainder of a pile of sheets is well-known in the art, it is not deemed necessary to enter into a detailed description of such operation in this application, especially as the present invention pertains only to an attachment for such suction feet. However,

in the drawings I have illustrated a sufficient portion of a printing press to disclose the application of the improvement thereon.

The feed box contains a floating stock 60 table 1 which is adapted to be automatically raised as the sheets of paper are removed therefrom, such raising being effected in the usual manner. The transverse separator bar which is arranged above the stock or sheets 65 of paper on the table 1 is indicated by the numeral 2. The separator bar adjacent its ends is provided with the usual pins 3 arranged for movement through guides 4 and operated by the lifting levers 5 in the usual 70 manner. On the separator bar 2 there are the suction feet. Three suction feet are usually employed, the inner suction foot being indicated by the numeral 6 and the end suction foot by the numeral 7 respectively. The 75 feet are adjustably mounted on the bar 2, the means for latching the same adjusted being broadly indicated by the numeral 8. In accordance with the varying thicknesses 80 of the paper sheets to be raised by the suction feet, the apertures in the flat underface of each foot varies in size and arrangement, as disclosed in Figures 6, 7 and 8 of the drawings, a suction being created when the separator bar is moved, in the usual manner, toward the top sheet on the table 1, the table 1 being also afforded a step by step direction upwardly in the usual manner. The flexible pipes through which the air is drawn for creating the vacuum necessary in the suction are indicated, in the drawings by the numeral 9 respectively, but it has not been deemed necessary to illustrate or describe the manner in which such suction is created, it being well known in the art.

Each of the suction feet is substantially rectangular in plan, and it is my purpose to removably attach to the outer or end suction feet 7 blower feet 10, in accordance with this invention. As disclosed in Figure 5 of the drawings, the blower foot 10 is in the nature of a cross sectionally rectangular hollow member having one end provided with an angle tubular extension 11 formed at its outer end with a reduced neck portion 12 that terminates in a rounded boss or bead 13 for the reception of the ends of the flexible branch air conducting pipes 14. As disclosed in Figure 2 of the drawings, the branch pipes are connected by an angle 110 coupling 15 to the main air conducting pipe 16, the said pipe 16 having its passage con-

trolled by a valve 17 and having therein a check valve 18 to prevent the outflowing of air therethrough. The pipe section in which the valve 17 is arranged is connected by a T to the supply pipe 18. I do not wish to be restricted to the precise manner in which the air is forced through the shoes 10, nor to the mechanism which regulates or controls the passage of air there-through, it being, however, essential that the air be forced through the feet 10 at the same interval that the suction is created between the feet 6 and 7 and the top sheet on the table 1.

15 Each foot 10 has its inner straight side provided with any desired number of air outlet apertures 19, and has its upper flat face provided with a laterally extending metallic strip 20 that terminates in a downwardly directed lip 21. The lip 21 may be arranged at an inward angle, and is designed to engage with one of the sides or edges of the foot 7 to effectively hold the foot 10 against the outer side or edge of the 25 said foot 7.

By means of my improvement, air is forcibly ejected at the desired interval between the top sheet and the remaining sheets on the table 1, so that danger of the top sheet 30 adhering to the next sheet will be positively prevented. In addition to this the feet 10 serve as guides for directing the suction feet to the pile of sheets. The improvement is of an extremely simple nature, and 35 may be cheaply manufactured and readily

applied to any pneumatic sheet separating device for printing presses.

Having described the invention, I claim:—

1. The combination with a suction foot 40 for drawing the top sheet from a pile of sheets, of means for injecting blasts of air between the top sheet and the sheet next thereto when a suction is created between the suction foot and the top sheet, said means comprising an air conducting apertured foot member arranged along one side of the suction foot, a laterally extending plate on said member disposed over the top of the suction foot, and spring means on the end of 50 said plate for contacting the side of the suction foot.

2. The combination with a suction foot for drawing the top sheet from a pile of sheets, 55 of means for injecting blasts of air between the top sheet and the sheet next thereto when a suction is created between the suction foot and the top sheet, said means comprising a hollow substantially rectangular member having an angle extension terminating in a nipple to which an air conducting hose is attached, said member designed to be arranged along one side of the suction foot and having spaced apertures therethrough, and clamping means carried by the member 60 for holding the same against the suction foot.

In testimony whereof I affix my signature.

BERT DECK.
